(57) **CLAIM**

The ornamental design for a carrier housing, as shown and described.

DESCRIPTION

FIG. 1 is a rear elevation view of the carrier housing of the present invention;

FIG. 2 is a front elevation view of the carrier housing of the present invention;

FIG. 3 is a right side elevation view of the carrier housing of the present invention;

FIG. 4 is a left side elevation view of the carrier housing of the present invention;

FIG. 5 is a top plan view of the carrier housing of the present invention; and,

FIG. 6 is a bottom plan view of the carrier housing of the present invention.

The portions of the carrier housing shown in broken lines form no part of the claimed design.
